Robert W. Erikson, Rockford, Ill., assignor to Sundstrand
Corporation, a corporation of Illinois

Filed Jan. 2, 1962, Ser. No. 68,151

Term of patent 14 years

(Cl. D65—1)

Fig. 5.

Fig. 6.

FIGURE 1 is an elevational view of one end of an oil burner pump embodying my new design;

FIGURE 2 is a top plan view thereof;

FIGURE 3 is a bottom plan view thereof;

FIGURE 4 is an elevational view of the end opposite to that shown in FIGURE 1;

FIGURE 5 is a perspective view taken from the left-hand corner of FIGURE 1, with portions omitted for convenience of illustration; and

FIGURE 6 is a perspective view taken from the left-hand corner of FIGURE 4, with portions omitted for convenience of illustration.

The dominant features of my design reside in the portions shown in full lines.

I claim:

The ornamental design for an oil burner pump, as shown and described.
